PISTON STRUCTURE

Fred F. Chamlee, Gatesville, Tex.

Application April 20, 1943, Serial No. 483,773

5 Claims. (Cl. 309—11)

This invention relates to new and useful improvements in piston structures for internal combustion engines.

At present, the element of an internal combustion engine which causes the most frequent and most expensive trouble is the piston, which is constantly subject to tremendous heat and abrasive friction during the normal operation of its complementary engine.

It is the principal object of the present invention in an appreciable manner to correct and alleviate some of the weak points of the present-day internal combustion engine pistons by presenting a piston which will have no "slap" action and which will present several features which will cause a guiding and true movement of the piston with the result that there will be no undue wear on any particular place of the piston.

Another important object of the invention is to provide a piston structure wherein the head thereof is constructed in an unusual manner and in a manner complementary to certain other portions of the piston so as to offer a unique means for preventing the escape of pressure due to uneven wear of the piston in any respect.

Still another important object of the invention is to provide a piston which has certain skirt portions, a head portion and certain expansion compensating features, all of which cooperate to present a piston which will retain its precise original shape over a far more considerable period of time than is possible with present-day pistons.

Other objects and advantages of the invention will become apparent to the reader of the following description.

In the drawings:

Figure 1 represents a side elevational view of the piston located within the cylinder, the latter being shown in vertical section.

Figure 2 is a side elevational view of the piston with the oil ring and piston head rings removed.

Figure 3 is a vertical sectional view on the line 3—3 of Figure 2.

Figure 4 is a horizontal section on the line 4—4 of Figure 2.

Figure 5 is a fragmentary enlarged sectional view through the head portion of the piston.

Referring to the drawings wherein like numerals designate like parts, it can be seen that numeral 5 generally refers to the improved piston, the same being situated in a conventional cylinder 6, as shown in Figure 1.

The piston 5 consists of a head portion 7, a reduced intermediate portion 8 and upper and lower skirt portions 9, 10 situated above and below the reduced intermediate portion 8.

5 In the head 7 are packing ring grooves 11 for accommodating rings 12.

The upper portion of the piston has a multiplicity of vertically disposed slots 13 extending from a point just above the skirt 9 to a point just within the reduced portion 8. The purpose of these slots will be more fully brought out hereinafter.

At the upper portion of the skirt 10 is an oil groove for accommodating an oil ring 14.

Of importance is the fact, that bearings 15, 15 for accommodating the usual wrist pin 16, on which is the upper bearing of the complementary piston rod 17, located within the skirt 10, instead of at an intermediate portion of the piston.

10 In other words, the upper limits of the lines of force do not pass much beyond the intermediate portion of the piston, with the result that this in itself reduces considerable of the "slap" action of present-day pistons.

20 Now referring to another important feature, and that is, the downward slope of the lands 18 at the head 7 of the piston. These lands 18 are preferably curved downwardly to a substantial point 18a, which pointed edge is flush with the peripheries of the aprons 9, 10.

25 Obviously, there will be considerable more expansion of the head 7 of the piston than the lower skirt portion 10 and to take care of this differentiation, the slots 13 are provided. In other words, the expansion of the skirt 10 will be strictly radial, while the expansion of the skirt 9 which would normally be greater than the skirt 10 is not only radial but also circumferential in that some of the expansion is taken up by the slots 13.

30 Therefore, it can be seen that as the piston heats up the fine or substantially sharp edges 18a of the lands 18 will press against the wall of the cylinder 6 and wear in uniformly, inasmuch as there is no tendency of the piston to "slap" as it is being precisely guarded by the riding action of the skirts 9, 10 against the wall of the cylinder. Thus a compensating or neutralizing means is provided for unequal expansion of different parts of the piston.

35 Therefore, it can be seen that while the upper skirt 9 will have a greater ratio of expansion than the skirt 10, this increase will be neutralized by the presence of the slots 13 and this feature is taken into consideration with the fact that the head 7 will expand most of all due to its

extreme hot position and, therefore, at the critical heat temperature of the cylinder, the fine edges 18a of the lands 18 will have worn away just sufficient enough to snugly wipe the cylinder wall, thus affording a head structure which machines itself into a perfect fit under the conditions of operating engine heat expansion.

At this point, it should be understood, that when the piston is initially placed in the cylinder, there is no clearance between the fine edges 18a of the lands 18 and the cylinder wall. Obviously, when the engine is operating and the head 1 is hot it expands and it is this frictional engagement of the edges 18a which results in the perfect breaking in of the head in the cylinder, with the cooperation of the guiding skirts 9, 10 and the specific location of the wrist pin bearings 16, all of which go together to eliminate "slap" action which has heretofore caused irregular wear of pistons.

It can also be observed, that on the down stroke of the piston, the packing rings will displace lubricant from the cylinder wall and onto the beveled lands, while on the up-stroke this lubricant is forced by said lands against the wall of the cylinder for uniform lubrication between the piston and said cylinder wall.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

- 5 1. An internal combustion engine piston comprising a head, a depending structure, a skirt just below the head, a skirt at the lower portion of the structure, and a reduced portion between the skirts, longitudinal slots being provided in said reduced portion extending into said head skirt.
- 10 2. An internal combustion engine piston comprising a head, a depending structure, a skirt just below the head, a skirt at the lower portion of the structure, and a reduced portion between the skirts, and a piston rod connection at the lower skirt, longitudinal slots being provided in said reduced portion extending into said head skirt.
- 15 3. An internal combustion engine piston comprising a head, a depending structure, a skirt just below the head, a skirt at the lower portion of the structure, and a reduced portion between the skirts, said upper skirt and adjacent reduced portion being vertically slotted parallel to the piston axis.
- 20 4. A piston comprising a body having a head portion, said body having upper and lower skirts, the upper skirt being slotted parallel to the axis to neutralize unequal expansion between the lower and upper skirt.
- 25 5. A piston comprising a body having a head portion, said body having upper and lower skirts, the upper skirt being slotted parallel to the axis to neutralize unequal expansion between the lower and upper skirt, the portion of the body between the skirts being reduced in circumference.

FRED F. CHAMLEE.
